UNITED STATES PATENT OFFICE.

FLORENT HINNEKENS, OF PATERSON, NEW JERSEY.

REDUCTION-GEAR UNIT.

Application filed July 10, 1923. Serial No. 650,630.

To all whom it may concern:

Be it known that I, FLORENT HINNEKENS, a citizen of the United States, residing at Paterson, in the county of Passaic and State of New Jersey, have invented certain new and useful Improvements in Reduction-Gear Units, of which the following is a specification.

This invention relates to reduction-gear units having means to make and break the driving connection, and in particular to reduction-gear units in which the reduction gearing and the make-and-break means are both contained in a casing wherein is also adapted to be contained liquid for lubricating the moving parts. In these mechanisms as heretofore constructed it has been impossible to lubricate adequately the actual working surfaces without the oil being thrown onto other surfaces of the moving parts within the casing and so finding its way in appreciable quantity out of the casing, which in most cases is very undesirable because it then becomes thrown off by centrifugal force and creates an unclean condition in the vicinity of the mechanism and possibly damages goods in process of manufacture, unless unduly elaborate packing of the parts to prevent escape of the oil is resorted to.

Given a hollow casing in which the lubricant body therein is adapted to have its level maintained relatively low, I journal a projecting-in shaft and a projecting-out shaft therein in such manner that, intersecting each other, the former is below the latter, and I fix on the former, which is the drive-shaft, a worm and on the latter or driven shaft I arrange, loosely revolute thereon, a worm-wheel, meshing with each other; on the driven or upper shaft I place means to disconnectively connect the worm-wheel and said shaft including a clutch member beside the worm-wheel and splined on said shaft. I further provide means to convey the lubricant up between and deliver it in limited quantity, as by spraying, onto working surfaces of both the worm-wheel and the mentioned disconnective connecting means.

By this arrangement only so much lubricant as is needed is applied and that only to the actual working surfaces; and even if

the worm dips in the oil, since all splashing is eliminated the oil is applied to none but the actual working surfaces. In consequence I produce a reduction-gear unit having means to make and break the driving connection which by extensive use in practice has proven to be adequately lubricated and also entirely without free exterior oil.

In the drawings,

Fig. 1 is a side elevation of the improved gearing unit;

Fig. 2 is a view mainly in vertical central transverse section;

Fig. 3 is a fragmentary central vertical section, illustrating principally the pump; and

Fig. 4 is a sectional view on line 4—4, Fig. 3.

The support for the moving parts includes a casing having an elongated base *a*. The lower part *b* of the casing has in plan an elongated form, approximating the length of but narrower than the base and it is laterally offset to the left (Fig. 2) on the same. The upper part *c* of the casing is circular in side elevation, having a diameter approximating the length of part *b*, and it has at its right side a circular reduced extension *d*. This extension and the left side of the casing part *c* have outwardly flanged and alined openings *e* *f*, which respectively receive, suitably secured to the casing, a simple form of gland *g* and a cap *h*. The ends of part *b* of the casing also have alined openings *b'* *b''*, respectively receiving a simple gland *i* and a cap *j* suitably secured to the casing.

Anti-friction bearings *k* are arranged in the gland *i* and cap *j* and in these is journaled the drive-shaft *l* which may protrude through the gland, as shown, and have connected with its protruding end any means for rotating it. On this shaft is fixed the worm *m*.

Anti-friction bearings *n* are also arranged in the opening *e* and cap *h* and in these, at right angles to the shaft *l*, is journaled the driven shaft *o*, which has suitably revolute on a bushing *o'* thereon the worm-wheel *p*, which is arranged in the circular upper part *c* of the casing and meshes with the worm *m*. The hub-portion *p'* of the worm-wheel is formed as a clutch of the

claw type, with its teeth projecting laterally, toward the extension *d* of the casing.

In said extension of the casing is housed the movable member *g* of the clutch, which 5 is also of the claw type, with its teeth projecting toward the clutch member formed by hub-portion *p'*; this clutch member *g* is suitably splined, as at *r*, on the shaft *o* so that it rotates therewith but may slide thereon 10 toward and from clutch member *p'*. Said clutch member *g* is a ring having a peripheral groove *g'* in which are engaged the diametrically opposite roller projections *s* of a fork *t* which is suitably fixed on the 15 upper end of a vertical rock-shaft *u* journaled in the extension *d* and base *a* of the casing at the right side of the latter. When the rock-shaft is rocked one way or the other the clutch member *g* is shifted into 20 or out of engagement with clutch member *p'* thus to cause shaft *o* to be driven from shaft *l* through the worm and worm-wheel or remain at standstill.

To facilitate forming the casing and assembling the parts the casing may be constructed in two parts, divided horizontally in a plane substantially coincident with the center of the upper circular part *c* of the casing. The liquid lubricant may be supplied to the casing at a filling inlet *b*³ having a normally closed cap *b*⁴ and arranged at the maximum level which it is intended the lubricant should assume, i. e., always below 25 all moving parts (Fig. 2). The lubricant is carried up and fed to the parts in the quantity required for the proper working thereof without excess, as follows:

Attached to the cap *j* at its inner end is a shell or casing consisting of a circular thick 40 disk *x* having a circular recess *z* formed in one face thereof and covered by a circular plate *y*, the recess being eccentric with respect to shaft *l* which penetrates the disk and its plate centrally thereof. In this recess is journaled an internally toothed 45 pump-member 2 and on the shaft is fixed to rotate therewith an externally toothed pump-member 3 which is of less diameter than pump-member 2 and has its teeth meshing with those of the latter, the intermesh of course only involving some of the teeth of each member at any time. Fitting the space between the unmoving parts of 50 these members is a fixed crescent-shaped 55 piece *2'*. At one side, as below, the point of closest approximation of the members a port 4 leads upwardly through the disk and delivers laterally into the recess *z*, said port having preferably an upwardly opening 60 check-valve 4', and at the other side, as above, said point another port 5 leads laterally from said recess and then upwardly through the disk. A pipe 6, dipping into the liquid lubricant in the casing part *b*, is 65 attached to the disk and communicates with

port 4; another pipe 7 is attached to the disk and communicates with port 5, being bent up and over the worm-wheel and provided with spray-outlets 7' for spraying with lubricant the clutch member *g* and the 70 teeth of the worm-wheel. Thus the main moving parts receive adequate lubricant, but only in such limited quantity that there is no excess to work out of the casing and no occasion for resort to elaborate types of 75 stuffing-boxes or glands to prevent its escape. Only such a gland *g* is necessary as will prevent escape of the lubricant as the effect of capillary attraction. The rotation of the shaft being in the direction of the arrow in Fig. 4 it will be seen that where 80 port 4 communicates with recess *z* the intermeshing teeth of the pump-members cause suction and where port 5 leads from said recess they cause compression of the liquid thus sucked in, so that while the shaft is rotating the liquid is caused to flow continually up through pipe 6, the recess *z* and pipe 7. Each time the lubricant is 85 drawn into the space between two teeth of either pump-member it is retained therein by opposite surfaces of the crescent-shaped piece *2'* until such space approximates the outlet 5; otherwise stated, said surfaces confine the lubricant contained in each space 90 against radial displacement from the time it enters the space at inlet 4 until it is to be delivered at outlet 5.

Having thus fully described my invention, what I claim as new and desire to secure by Letters Patent is:

1. In combination, a substantially closed upright casing, a horizontal drive-shaft projecting into the casing and a horizontal driven shaft protruding from the casing 105 at a right angle to and above the drive-shaft and both journaled in the casing, a worm fixed on the drive-shaft and a worm-wheel meshing therewith and revoluble on the driven shaft, means to disconnectively 110 connect said worm-wheel and driven shaft including a clutch member beside the worm-wheel and slideable on the driven shaft, the casing being adapted to contain lubricant below the worm, and means to convey the 115 lubricant up and deliver it onto working surfaces of the worm-wheel and first-named means in limited quantity.

2. In combination, a substantially closed upright casing, a horizontal drive-shaft 120 projecting into the casing and a horizontal driven shaft protruding from the casing at a right angle to and above the drive-shaft and both journaled in the casing, a worm fixed on the drive-shaft and a worm-wheel 125 meshing therewith and revoluble on the driven shaft, means to disconnectively connect said worm-wheel and driven shaft including a clutch member beside the worm-wheel and slideable on the driven shaft, the 130

casing being adapted to contain lubricant below the worm, and means to convey the lubricant up and deliver it onto working surfaces of the worm-wheel and first-named means in limited quantity including a delivery pipe extending up between them and having a spray outlet opening toward said

first-named means and having its upper end extending over the worm-wheel and having a spray outlet opening downward toward 10 the toothed surface of the latter.

In testimony whereof I affix my signature.

FLORENT HINNEKENS.
